(57) **CLAIM**

The ornamental design for the ear protection device, as shown and described.

DESCRIPTION

FIG. 1 is a bottom perspective view of the present invention; and

FIG. 2 is a top perspective view thereof; and

FIG. 3 is a rear side view thereof; and

FIG. 4 is a front side view thereof; and

FIG. 5 is a bottom view thereof; and

FIG. 6 is a top view thereof; and

FIG. 7 is a left side view thereof; and

FIG. 8 is a right side view thereof; and,

FIG. 9 is a perspective view thereof in a human ear. Wherein the dotted lines herein illustrate environment and use and do not form any part of the claimed design.
